ABSTRACT: An implosion resistant cathode ray tube for television display employing a first metal band surrounding and secured to the envelope adjacent the screen and a second metal, preferably steel, band around the first band and subjected to a large tensile stress. The second band glides over the first and to equalize tension at the corners, a lubricant is applied between the bands to reduce friction between the bands. As a lubricant, beeswax is preferred.

CATHODE RAY TUBE IMPLOSION GUARD WITH BEESWAX BETWEEN ANNULAR METAL FRAME AND METAL BAND

The invention relates to a television display tube having an implosion guard which consists of a metal ring which is stuck, for example, to the tube, and of at least one steel band arranged around the ring and subjected to a large tensile stress.

As is known, television display tubes must be provided with an implosion guard which prevents the glass body from being completely destroyed when air suddenly penetrates into the tube. As is known, in such an implosion guard, annular frames of a corrosion-resistant sheet iron are used which are provided with reinforcing ribs and with lugs at the corners for securing the display tube in the cabinet of a receiver. These bands are pressed over the tube from the neck as far as the mould match line and are surrounded by at least one steel band subjected to a large tensile stress.

Experiments have shown that the implosion guard of such television display tubes is effective when annular frames and clamping bands are used and is based on the occurrence of force components directed approximately along the diagonals. However, great difficulty was involved in determining the pressure forces which were absolutely sufficient to prevent an implosion. The experiments for determining these forces at the corners have shown that these forces can be greatly different at the separate corners of a tube, since the clamping band, when stretched around the annular frame, is subjected to friction, especially at the areas at which the direction of the steel band strongly changes, i.e. at the corners of a rectangular television display tube.

The frictional forces are produced between the steel band and the annular frame or between separate steel bands if several juxtaposed steel bands are stretched around the annular frame. The invention is based on recognition of the fact that it is essential to provide the steel bands on the annular frame so that the forces produced at the separate corners of the display tube are the same. According to the invention, this may be achieved by reducing the coefficients of friction between the annular frame and the steel band or between the separate steel bands. For this purpose, according to the invention, a conditioner, preferably beeswax, is applied between the metal bands, at least near the corners of the display tube, i.e. at areas at which a great frictional force is to be expected. With the use of two juxtaposed steel bands, the conditioner may be applied both between these steel bands and between the lower steel band and the annular frame near the corners. If the conditioner is applied in manner, the coefficient of friction at the critical points is reduced to such an extent that a uniform distribution of force at the corners of the display tube is obtained without the stretching machine sliding off along the bands. However, it is also recommendable to apply a conditioner to the inner sides of the beginning and the end of a band sliding over each other and clamped by the stretching device, because the tensile force produced in the band by the stretching device is a maximum when the friction between the band and the stretching device is a maximum and that between the beginning and the end of a band is a minimum.

Known steel bands are generally manufactured for packing applications and are lubricated with oil in order to permit the bands to more readily sliding over each other and to reduce the coefficients of friction. This step is sufficient for the normal packing applications, it is true, since it is not essential that

a given pressure should be exerted on the corners of a packed article; it is only important that the packing should be kept intact. As already stated, however, it is of major importance with the use of such steel bands for protecting television display tubes from implosion that equal forces should be produced at the separate corners of the tube and that these forces should lie within certain limits during the stretching operation, for example, between 900 and 1000 kgs/corner.

The present invention therefore has the advantage that the coefficient of friction between clamping band and annular frame or between band and band can be reduced to such extent that a uniform distribution of forces over the four corners of a television display tube is obtained.

The invention will now be described more fully with reference to the accompanying drawing, in which:

FIG. 1 is a plan view of a television display tube which is provided with an implosion guard consisting of an annular frame and a steel band;

FIG. 2 shows on an enlarged scale a part with two corners of an approximately rectangular television display tube; and

FIG. 3 shows the corner of a television display tube of FIG. 1, the implosion guard now consisting of an annular frame and two juxtaposed steel bands.

Referring now to FIG. 1, reference numeral 1 denotes the television display tube, viewed from the screen side, over the periphery of which is passed an annular frame 2 which is provided at its corners with lugs 3 for securing the tube in the cabinet of a receiver and is surrounded by a steel-clamping band 4 (shown in dotted lines).

In FIG. 2, reference numeral 1 also denotes the television display tube, reference numeral 2 the annular frame, reference numeral 3 the lug and reference numeral 4 the steel-clamping band. This FIG. shows a television display tube the screen of which is located on the front side of the cabinet of the receiver, the glass of the sidewall of this tube being painted dark at 5 between the display screen and the bands.

FIG. 3 shows an embodiment in which the annular frame 2 provided with the securing lugs 3 is surrounded by two juxtaposed steel bands 4 and 6.

According to the invention, conditioners, preferably consisting of a beeswax, are applied at least within the region limited by transverse lines 7 between the parts sliding with friction over each other, i.e. between the annular frame 2 and the steel band 4 or between the annular frame 2, the steel band 4 and the steel band 6. These conditioners cause the coefficients of friction between the various bands to be reduced to such an extent that the bands can be pulled across the corners without difficulty and that equal forces are produced at all the corners of the television display tube.

The use of such conditioners also affords the advantage that the steel bands need not be pulled so tightly that they are liable to break.

I claim:

1. A cathode-ray tube for television display having a substantially rectangular window portion and a conical portion adjoining the window portion, an annular metal frame surrounding and secured to the conical portion adjacent the junction thereof with said window portion, a metal band under tensile stress surrounding the annular metal frame, and a lubricant consisting of beeswax between the metal band and the metal frame to reduce the coefficient of friction therebetween whereby the band can be drawn over the frame and the distribution of force at the corners is made uniform.
